UNITED STATES PATENT OFFICE.

ALBERT J. GURNEY, OF CANTON, OHIO, ASSIGNOR TO THE AMERICAN MINE DOOR CO., OF CANTON, OHIO, A CORPORATION OF OHIO.

WIRE HANGER.

Application filed June 14, 1924. Serial No. 720,074.

To all whom it may concern:

Be it known that I, ALBERT J. GURNEY, a citizen of the United States, residing at Canton, in the county of Stark and State of Ohio, have invented certain new and useful Improvements in Wire Hangers, of which the following is a specification.

This invention relates to an improved wire hanger of the general character disclosed in my co-pending application for wire hanger, filed June 14, 1924, Serial No. 720,073, and seeks to provide a device of this character embodying a pair of jaws and wherein the adjustable clamping means employed at the ends of the jaws for drawing the jaws together will be mounted independently of the jaws so that adjustment of said clamping means will not cause mutilation of any portion of the jaws while said adjusting means may be repaired or renewed without the necessity for repairing or renewing the jaws.

Other and incidental objects will appear hereinafter.

In the drawings:

Figure 1 is a side elevation of my improved hanger,

Figure 2 is a vertical sectional view taken medially between the jaws of the hanger,

Figure 3 is a detail transverse sectional view on the line 3—3 of Figure 2, looking in the direction of the arrows.

Figure 4 is a transverse sectional view on the line 4—4 of Figure 2, looking in the direction of the arrows, and

Figure 5 is a view similar to Figure 2, showing a slightly different embodiment of the invention.

In carrying the invention into effect, I employ a pair of mating oblong jaws 10 and 11 which are grooved at their lower margins, as at 12, to receive a wire, as for instance, a trolley wire, conventionally shown at 13. Above the groove 12, the jaws are shaped to form a closed barrel 14 and extending from the end walls of the barrel are alined tapered nipples 15 having smooth outer faces, a half of each nipple being integral with each jaw respectively. Formed on the end wall portions of the jaw 11 are, as shown in Figure 3, pairs of projecting centering lugs 16 abutting the end wall portions of the jaw 10 at their inner sides for locking the jaws against relative movement and rising from the jaw 10 medially thereof is an internally

threaded sleeve 17 while the jaw is similarly provided with an upstanding flange or half-collar 18 fitting said sleeve. Extending transversely of the barrel portions of the jaws from the base end of said sleeve and collar portion are pairs of alined reinforcing webs 19 notched to define openings registering with the nipples 15.

In conjunction with the jaws 10 and 11, I provide a tubular rod 20 which is formed to extend through the nipples 15 and through the openings of the webs 19 between the jaws and screwed upon the ends of said rod are cap nuts 21 tapered internally to fit over the nipples 15 and provided with smooth inner faces to coact with said nipples. The rod 20 is formed to receive a wire insulator 22 therethrough which insulator may accommodate a signal wire, or the like, as conventionally illustrated at 23. Thus, as will be seen, the nuts 21 may be adjusted upon the rod 20 over the nipples 15 for drawing the jaws 10 and 11 toward each other clamping the jaws in engagement with the wire 13 as well as in engagement with the rod 20 for rigidly supporting the wires 13 and 23 in spaced relation.

In use, a supporting insulator, as conventionally illustrated at 24, will be preferably provided in conjunction with the hanger. This insulator may be of any approved type but will include a threaded stud 25 to accommodate the sleeve 17 of the jaw 10. Thus, the sleeve may be screwed upon the stud for mounting the jaw 10 when, after the wire 13 and wire 23, with the insulator 22, rod 20 and nuts 21 have been arranged in position, the jaw 11 may be assembled with the jaw 10 and the nuts 21 adjusted, as previously indicated, for tightly clamping the parts together.

Attention is now directed to the fact that since the nuts 21 are formed with smooth internal faces to coact with the smooth external faces of the nipples 15, while said nuts are mounted upon the rod independently of the nipples, repeated adjustment of the nuts or extremely tight adjustment thereof cannot serve to injure the nipples. On the other hand, any injury which may be inflicted in the practical use of the device, will occur either to the nuts or to the rod and, as will be appreciated, these parts

- may be renewed without the necessity for renewing or replacing the jaws. Since the nuts are provided with a straight threaded bore, the nuts may be easily retapped or supplanted and, likewise, the rod 20 may be repaired or supplanted at small cost. Accordingly, the hanger may at all times be kept in efficient condition at but little expense.
- 5 10 In any instance where the wire 23 is a feed wire for supplying the trolley wire 13 with current, the insulator 22 is eliminated so that the feed wire will extend through the tubular rod 20 directly in contact therewith. Thus, under such conditions, the hanger will provide a direct electrical connection between the wires for distributing the current from the feed wire to the trolley wire.
- 15 20 In some instances, it may prove desirable to use the hanger in conjunction with a single wire and to meet such a situation, I accordingly provide a slightly different embodiment of the invention, as illustrated in Figure 5 of the drawings, wherein a solid rod 26 is employed in lieu of the tubular rod 20 as illustrated in connection with the prior embodiment of the invention. The rod 26 is formed to extend through the nipples 15 between the jaws 10 and 11 and is threaded at its ends to receive the nuts 21 which, as will be appreciated in view of the foregoing description, may be adjusted over the nipples for drawing the jaws together and clamping a wire, as conventionally illustrated at 27, between the lower margins of the jaws in the groove 12.
- 25 30 Having thus described the invention, what I claim is:
- 35 40 1. A hanger of the character described including coacting jaws to engage a wire, and rotatable independently adjustable means slidably coacting with the jaws securing the jaws together.
- 45 50 2. A hanger of the character described including coacting jaws to engage a wire and formed to receive a second wire therebetween, and rotatable means slidably coacting with the jaws securing the jaws together.
- 55 60 65 3. A hanger of the character described including coacting jaws to engage a wire and provided at their ends with projections, and rotatable independently adjustable means slidably coacting with said projections securing the jaws together.
- 70 75 80 85 90 95 100 105 110 115 120 125 130 4. A hanger of the character described including coacting jaws to engage a wire and formed to receive a second wire therebetween, the jaws being provided at their ends with projections, and rotatable means slidably coacting with said projections securing the jaws together.
5. A hanger of the character described including coacting jaws provided with por-
- tions projecting from the ends of the jaws longitudinally thereof, and independently adjustable means slidably coacting with said jaw portions securing the jaws together.
6. A hanger of the character described including coacting jaws provided with portions projecting from the ends of the jaws longitudinally thereof, and independently adjustable means slidably coacting with said jaw portions wedging the jaws toward each other.
7. A hanger of the character described including coacting jaws provided with portions projecting from the ends of the jaws longitudinally thereof, and independently adjustable means fitting over said jaw portions slidably coacting therewith wedging the jaws toward each other.
8. A hanger of the character described including coacting jaws provided at their ends with nipple portions mating to define nipples at the extremities of the jaws, and independently adjustable means slidably fitting over said nipples securing the jaws together.
9. A hanger of the character described including coacting jaws to engage a wire, companion independently adjustable means at the ends of the jaws securing the jaws together, and means independent of the jaws mounting said securing means.
10. A hanger of the character described including coacting jaws to engage a wire, independently adjustable means wedging the jaws toward each other, and means independent of the jaws mounting said wedging means.
11. A hanger of the character described including coacting jaws, companion independently adjustable means at the ends of the jaws securing the jaws together, and means accommodated between the jaws mounting said securing means.
12. A hanger of the character described including coacting jaws to engage a wire, independently adjustable means to coact with the jaws for drawing the jaws together, and means accommodated between the jaws adjustably mounting said first mentioned means.
13. A hanger of the character described including coacting jaws to engage a wire and provided with portions projecting at the ends of the jaws longitudinally thereof, independently adjustable means slidably coacting with said jaw portions securing the jaws together, and means accommodated between the jaws adjustably mounting said securing means.
14. A hanger of the character described including coacting jaws to engage a wire and provided with portions projecting at the ends of the jaws longitudinally thereof, independently adjustable means coacting with said jaw portions wedging the jaws toward each other.

each other, and means accommodated between the jaws adjustably mounting said wedging means.

15. A hanger of the character described including coacting jaws to engage a wire and provided at their ends with nipple portions mating to form nipples at the extremities of the jaws, independently adjustable means coacting with said nipples securing 10 the jaws together, and means accommodated between the jaws mounting said securing means.

16. A hanger of the character described including coacting jaws to engage a wire 15 and provided at their ends with nipple portions mating to form nipples at the extremities of the jaws, independently adjustable means fitting over said nipples slidably coacting therewith and securing the jaws together, and means accommodated between the jaws adjustably mounting said securing 20 means.

17. A hanger of the character described including coacting jaws formed to receive an 25 insulator therebetween accommodating a wire, means securing the jaws together, and means independent of the jaws mounting said securing means.

18. A hanger of the character described 30 including coacting jaws to engage a wire and formed to receive an insulator therebetween accommodating a second wire, means securing the jaws together, and means independent of the jaws mounting said securing 35 means.

19. A hanger of the character described including coacting jaws to engage a wire, a rod accommodated between the jaws, and

means mounted on said rod securing the jaws together and independently adjustable 40 on the rod.

20. A hanger of the character described including coacting jaws to engage a wire and provided at their ends with nipple portions mating to define nipples at the extremities of the jaws, a rod accommodated between the jaws extending through said nipples, and nuts mounted upon the ends of the rod and independently adjustable over said nipples for securing the jaws together. 45 50

21. A hanger of the character described including coacting jaws to engage a wire and provided at their ends with nipple portions mating to define tapered nipples at the extremities of the jaws, a rod accommodated between the jaws extending through said nipples and nuts internally tapered to fit over said nipples and adjustable upon the rod for securing the jaws together. 55 60

22. A hanger of the character described including coacting jaws, a tubular rod accommodated between the jaws, and means mounted on said rod securing the jaws together. 65

23. A hanger of the character described including coacting jaws, a tubular rod accommodated between the jaws, means mounted on said rod securing the jaws together, and an insulator accommodated by 70 said rod and adapted to receive a wire therethrough.

In testimony whereof I affix my signature.

ALBERT J. GURNEY. [L. s.]
